EJECTOR BOX FOR A MOLD BASE

Ivar T. Quarnstrom, Detroit, Mich.

Application June 9, 1948, Serial No. 31,952

3 Claims. (Cl. 18—42)

1

This invention relates to standard mold bases used in conjunction with injection plastic molding, and more particularly to a novel ejector box construction for use in association with such standard mold bases.

The present invention provides a novel ejector box construction in association with the reciprocal ejector plate of the mold base.

Heretofore ejector plates have been actuated by an abutment element associated with the movable portion of a molding machine within which a standard mold base is mounted, or on the other hand such ejector plates have been reciprocally actuated by a reciprocal shaft which extends slidably through the mold base with its end joined to the ejector plate, various means having been heretofore contemplated for cooperative engagement with said shaft for reciprocally actuating the same.

It is the principal object of this invention to provide a novel ejector box construction for effecting reciprocal movements of the mold base ejector plate as desired.

It is the further object of this invention to provide a hollow substantially rectangular ejector box normally positioned upon the movable anchor plate of the mold base together with a pair of tubular guide elements joined to each other at right angles.

It is the further object of this invention to provide an ejector actuating shaft which incorporates a longitudinally arranged rack gear reciprocally slidably within one of said tubes, and a secondary reciprocally rotatable shaft guidingly positioned within said second tube and carrying a pinion in mesh with said rack gear.

It is the still further object of this invention to provide said tubes arranged to intersect each other at their central portions, and with the common intersecting surfaces thereof being cut away to provide communication between said tubes to permit cooperative meshing of the aforesaid pinion in one tube with the aforementioned rack gear slidably positioned within the intersecting second tube.

These and many other objects will be seen from the following specification and claims in conjunction with the appended drawing in which:

Figure 1 is a perspective view of a mold base including an ejector box.

Figure 2 is a top plan view of the ejector box with the ejector plate removed for illustration.

Figure 3 is an elevational section on line 3—3 ⁵⁵

2

of Figure 2, but with the ejector plate shown in phantom.

Figure 4 is an elevational section on line 4—4 of Figure 2 also showing the ejector plate in phantom; and

Figure 5 is a plan view of the two intersecting guide tubes normally positioned within the ejector box as shown in Figure 2.

It will be understood that the above drawing illustrates merely a preferable embodiment of the invention, and that other embodiments are contemplated within the scope of the claims hereafter set out.

As generally indicated in Figure 1 the mold base includes movable anchor plates 11 upon which the ejector box is mounted, the latter being generally indicated by the numeral 12. Anchor plates 11 are rectangular strips upon which ejector box 12 is mounted, being suitably secured thereto as by welding.

A backup plate 13 is mounted upon the top of the ejector box 12 in parallel relation to anchor plates 11 and carries thereon a suitable cavity retainer plate 14.

A stationary anchor plate 15 is shown mounted in parallel relation to retainer plate 14 and carrying thereunder the upper cavity retainer plate 16, there being a plurality of dowel pins 17 which depend downwardly from retainer plate 16.

Corresponding guiding dowel pin openings are formed within cavity plate 14 to cooperatively receive said dowel pins when plates 14 and 15 are brought into cooperative engaging relation for the molding operation.

The above description merely sets out the association of the various elements which make up the standard mold base, within which is employed an ejector box 12 hereafter to be described in conjunction with Figures 2, 3, 4 and 5 of the drawing, said ejector box and its construction being the subject matter of the present disclosure.

Referring to the drawing the ejector box generally indicated at 12 consists of a pair of upright spaced parallel plates 18 and 19 suitably mounted and secured upon the top of anchor plates 11 adjacent their edges. It will be noted that backup plate 13 is positioned upon and suitably secured to the top edges of parallel plates 18 and 19.

As viewed in Figures 1 and 2 the ejector box includes the end wall plates 20 and 21 as well as the intermediate plates 22 and 23, all of which lie in parallel spaced relation within upright

parallel plates 18 and 19, being arranged at right angles thereto.

The plates 20, 21, 22 and 23 are immovably secured in upright position between anchor plates 11 to thereby provide the end walls for the ejector box, in association with its parallel side walls 18 and 19. The intermediate spaced upright walls 22 and 23 divide the ejector box into the two compartments 24 and 25.

The ejector box is completed by the cover 26 which is interposed between the side walls 18 and 19 and mounted and secured upon the top edges of the respective upright plate elements, 20, 21, 22 and 23.

An upright tube 27 is centrally positioned within in compartment 25 with its lower end aligned with the bottom of anchor plate 11 and with its upper end formed of a reduced diameter at 28 being tightly projected up into a corresponding opening within cover 26.

Longitudinally reciprocal shaft 29 is slidably positioned within the upright tube 27 as shown in Figure 3 with its upper end normally extending slightly above the top surface of cover 26.

Shaft 29 has an upper portion 30 of reduced diameter which is press-fit within a corresponding opening in the central portion of ejector plate 31, or may be otherwise suitably secured thereto.

As shaft 29 extends partially above cover 26 before terminating in the portion of reduced diameter it is seen that said ejector plate is normally maintained in parallel spaced relation to the upper surface of cover 26.

A suitable rack gear 32 is longitudinally arranged throughout the length of shaft 29 with the outer edges of said gear cooperatively and slidably bearing against the inner surface of tube 27.

A second tube 33 is arranged at right angles to tube 27 with corresponding intersecting portions of tubes 27 and 33 being cut away to permit said tubes to be centrally interconnected as shown in Figure 5, said tubes being suitably secured to each other as by welding. As viewed in Figure 2 tube 33 extends through compartment 25 of ejector box 12 with its end portions 34 of reduced diameter being press-fitted within corresponding openings of the upright parallel plates 20 and 22.

Rotatable shaft 35 is journaled through tube 33, and through a corresponding second such tube 33 which is positioned within and through the other compartment 24 forming a part of ejector box 12, the construction and arrangement of the second tubular element 33 being identical with that above described with respect to the corresponding aligned tube within compartment 25.

It will be noted from the drawing that there are two sets of intersecting tubular elements 27 and 33 with one extending through each of the compartments 24 and 25 which form a part of ejector box 12. Naturally the secondary upright tube 27 is arranged in parallel spaced relation to the first mentioned corresponding tube 27 with its upper end being similarly secured through a corresponding opening in cover 26.

Furthermore there will be a second corresponding reciprocal shaft 29 within said second tube 27, also carrying a suitable longitudinally arranged rack gear.

Rotatable shaft 35 is thus journaled through both of the aligned supporting tubes 33, however it is contemplated that the ejector box may be

constructed with only one compartment, and with only one set of intersecting tubes 27 and 33.

The rotatable shaft 35 has formed thereon the pinion gear 36 which extends substantially through both of the aligned tubes 33, being in meshing engagement with both of the upright rack gears 32 which form a part of reciprocal ejector plate actuating shafts 29. On the other hand two separate pinions could be mounted upon shaft 35 in spaced relation for separate cooperating meshing engagement with the respective rack gears upon shafts 29.

The intersecting cutaway portions of the tubes 27 and 33 thus permit communication between the interiors of the tubes 27 and 33 thereby permitting the cooperating meshing engagement of pinion 36 with the corresponding rack gears 32, or one rack gear if only one such shaft 29 is employed.

The outer end 37 of shaft 35 is squared to permit the attachment of an actuating handle or other element whereby shaft 35 may be reciprocally actuated or rotated as desired to cause up or down movements of ejector plate 31.

As viewed in Figure 1 ejector plate 31 is slidably positioned above the cover 26 of ejector box 12 and between the upright side walls 18 and 19, there being a plurality of ejector plate return pins 38 which extend upwardly from said ejector plate and thru corresponding openings in plates 13 and 14.

In normal operation pins 38 extend above the surface of cavity plate 14 and are cooperatively engageable with the bottom surface of cavity plate 16 as the two plates 14 and 16 are brought together for the molding operation, said return pins 38 acting to project or return ejector plate 31 to its normal inoperative position as viewed in Figures 3 and 4.

Having described my invention, reference should now be had to the claims which follow for determining the scope thereof.

I claim:

1. In a mold base including stationary and movable anchor plates and cavity retainer plates associated therewith, an ejector box including in combination, parallel upright side walls on said movable anchor plates, a backup plate positioned over the tops of said walls and in supporting relation to a cavity retainer plate, an ejector box cover between said walls and in spaced relation to said backup plate, a reciprocal ejector plate extending between said cover and backup plate, an upright reciprocal shaft slidably positioned through said cover and joined to said ejector plate, a rack gear on said shaft, a transverse rotatable shaft carrying a pinion in mesh with said rack gear and extending outwardly from said mold base, and a pair of cylindrical tubes intersecting each other at their central portions and joined to each other at right angles with their common intersecting surfaces being cut away to provide communication between said tubes, and with their ends secured within said mold base, said tubes respectively providing guide supports within which said shafts are positioned.

2. In a mold base having a reciprocal ejector plate, the combination, of a hollow rectangular ejector box, a cover therefor below and in parallel relation to said ejector plate, a pair of tubes intersecting each other at their central portions and joined to each other at right angles with their common intersecting surfaces being cut away to provide communication between said tubes, the ends of one of said tubes supportably ex-

tending into the side walls of said box, with one end of the other tube being joined to and extending through said cover, a longitudinally reciprocal shaft carrying a rack gear slidably positioned within said second mentioned tube and joined at one end to said ejector plate, and a shaft carrying a pinion rotatably positioned within the other tube with said pinion in mesh with said rack gear.

3. The combination, of a hollow rectangular ejector box, a cover therefor, a pair of tubes intersecting each other at their central portions and joined to each other at right angles, with their common intersecting surfaces being cut away to provide communication between said tubes, the ends of one of said tubes supportably extending into the side walls of said box and secured thereto, with one end of the other tube being joined to and extending through said cover, a longitudinally reciprocal shaft carrying a rack

10

20

gear reciprocally slideable within the latter tube with one end projecting through and above said cover, a reciprocal ejector plate lying parallel to said cover and joined to said end, and a reciprocally rotatable shaft carrying a pinion journalled within said other tube and in mesh with said rack gear.
